Patented Feb. 16, 1926.

UNITED STATES PATENT OFFICE.

WILLY KNOLL, OF STUTTGART, GERMANY.

PROCESS FOR PRODUCING SHADING-OFF ORNAMENTATION ON LEATHER.

No Drawing.

Application filed October 12, 1925. Serial No. 62,174.

To all whom it may concern:

Be it known that I, WILLY KNOLL, a citizen of Germany, residing at Stuttgart, Germany, have invented certain new and useful 5 Improvements in Processes for Producing Shading-Off Ornamentation on Leather, of which the following is a specification.

The present invention relates to a process for producing shading-off color effects on 10 leather on a large scale and in any desired design. The invention can be carried out on any kind of leather, either directly on the leather or on a previously prepared background. In the present new process, 15 leather of any size can be so decorated and can be used for automobile and furniture upholstery, large table coverings, etc. The leather can be in any condition, such as smooth, rough, granulated or ribbed, depending upon the effect desired, and any 20 color schemes can be employed, either with or without a background.

In its broadest aspect the new process consists in covering a portion of the leather by 25 means of any suitable pattern device and to apply the color in any suitable manner such as spraying over the edge of the pattern which will completely color the leather immediately adjacent the edge of the pattern 30 but will shade off as the distance increases from the edge of the pattern. Such distance will of course be dependent upon the effect desired and can be regulated by using a more or less quantity of color. The pattern 35 can comprise any desired outline, which includes outlines in the shape of flowers, birds, trees, etc. The pattern can furthermore be provided with perforations which will allow the color to reach the leather through 40 the perforations; the essential feature being that a portion of the leather comprising any shape is covered and the color is applied in order to produce the shading-off effect. The color contains a fixing means, such as varnish or a nitrocellulose solution in order to 45 permanently bind the color to the leather, so that the color will not rub off during wear and will not crack when the leather is folded.

50 In order to obtain a complete understanding of the present process three specific examples will be set forth, giving in detail all of the steps of the process.

In order to obtain a specific shading-off 55 color effect on the leather in its natural color,

that is without any staining or other previous color preparation, the desired pattern is placed on the leather, that is a portion of the leather is covered, and the color containing the fixing means, is then applied directly on the leather by spraying under pressure or any other suitable manner until the desired amount of color has been applied to produce the shading-off effect. When a small pattern is used this can of course be 65 repeated at desired spaced intervals on the leather until the entire surface has been decorated. If a second color is desired, it is only necessary to repeat this step at a different angle or angles. 70

A second way of securing the desired effect is obtained by first staining, dyeing, varnishing, enameling or otherwise applying a background over the entire surface of 75 the leather and then placing the pattern on the leather, thus covering a portion thereof, whereafter a color is applied or sprayed over the edge of the pattern directly on the background. The background can of course 80 be any color and also the shading-off decoration can be of any desired color or shade and width.

A third way of carrying out this new process consists in applying a background, if desired, and then covering a portion of 85 the leather to thus apply or spray a color over the edge of the pattern. Then a second shading-off color effect can be carried out, either directly on the first shading-off color or on an unshaded portion at a different 90 angle, depending upon the effect desired.

It is of course understood that the steps of covering the leather and applying the color can be carried out in a repeated manner in order to cover the entire surface of 95 the leather to be decorated, or the color can be applied over the entire surface in a single step in order to produce the shading-off effects, depending upon the specific pattern required. It is therefore possible to mechanically produce a large decorated leather surface at a small cost and very little expenditure of time, and also to produce leather fabric having a limitless number of designs 100 in all colors and combinations. 105

I claim as my invention:

1. A process for producing a shading-off color effect on leather, which consists in the steps of covering a portion of the leather by means of a pattern; and then applying 110

a color containing a fixing means over the edge of the pattern to produce a shading-off effect.

2. A process for producing a shading-off color effect on leather, which consists in the steps of applying a background over the entire surface of the leather; covering a portion of the leather by means of a pattern; and applying a color containing a fixing means over the edge of the pattern on the background to produce a shading-off effect.
5. A process for producing a shading-off color effect on leather, which consists in the steps of applying a background over the entire surface of the leather; covering a portion of the leather by means of a pattern; and applying a color containing a fixing means over the edge of the pattern on the background to produce a shading-off effect.
10. A process for producing a shading-off color effect on leather, which consists in the steps of covering a portion of the leather by

means of a pattern; and then spraying a color containing a fixing means over the edge of the pattern to produce a shading-off effect.

15. A process for producing a shading-off color effect on leather, which consists in the steps of applying a background over the entire surface of the leather; covering a portion of the leather by means of a pattern; and spraying a color containing a fixing means over the edge of the pattern on the background to produce a shading-off effect.
20. A process for producing a shading-off color effect on leather, which consists in the steps of applying a background over the entire surface of the leather; covering a portion of the leather by means of a pattern; and spraying a color containing a fixing means over the edge of the pattern on the background to produce a shading-off effect.

In testimony whereof I affix my signature.
WILLY KNOLL.
